UNITED STATES PATENT OFFICE

MARIO FROSALI, OF NEW YORK, N. Y.

DESIGN FOR A DOLL

Application filed May 12, 1930. Serial No. 35,594. Term of patent 3½ years.

To all whom it may concern:

Be it known that I, MARIO FROSALI, a citizen of the United States, residing at New York, in the county of New York and State of New York, have invented a certain new, original, and ornamental Design for Doll, of which the following is a specification, reference being had to the accompanying drawing, forming part thereof.

The doll is a characterization of a fictitious character known as "Pinocchio" from the famous Italian story by that name written by Collodi.

Figure 1 is a front elevation showing my new design.

Fig. 2 is a side elevation.

I claim:—

The ornamental design for a doll as shown.

MARIO FROSALI.
